UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

THREAD TRIMMER FOR SEWING MACHINES.

Application filed January 16, 1924. Serial No. 686,626.

This invention relates to sewing machines of that type which are constructed to sew a short seam and then automatically come to rest, (a buttonhole sewing machine being an exemplification of this type of sewing machine), and particularly to a device for trimming the under thread at the end of the sewing operation, and also the cord, if one is used in making the buttonhole.

10 Buttonhole sewing machines are usually provided with work-holding means and stitch-forming mechanism and some buttonhole sewing machines are constructed so that when the machine comes to rest at the end 15 of the sewing operation, the work-holding means and stitch-forming mechanism are properly situated relative to each other for cutting the buttonhole slit, and when the machine is started in operation the work- 20 holding means and stitch-forming mechanism are first given a relative movement to carry the parts from buttonhole-cutting position to stitching position and then the stitch-forming mechanism is set in opera- 25 tion to form the edge stitches on the button- hole and the parts have a further relative movement to feed the work during the stitching on the buttonhole. When the stitching on the buttonhole has been com- 30 pleted the stitch-forming mechanism is brought to rest and the parts are given a further relative movement to carry them into buttonhole-cutting position.

In some sewing machines the buttonhole 35 is cut when the machine is first started in operation and before the stitching is performed and in other buttonhole sewing machines the cutting of the buttonhole takes place just before the machine is brought to rest and after the buttonhole has been 40 stitched. Furthermore some buttonhole sewing machines are provided with means for laying a cord along the edge of the button- hole as the stitching proceeds and one fea- 45 ture of the present invention relates to a novel mechanism which operates to cut not only the under thread but also the cord.

Another feature of the invention relates 50 to an improved device for drawing off a length of the under thread after the stitching on the buttonhole has been completed and before the cutting mechanism operates to cut said thread and cord, the amount of thread thus pulled off being sufficient to pro-

vide for the formation of the first stitch on 55 the next buttonhole.

In order to give an understanding of my invention I have illustrated in the drawings a selected embodiment thereof which will now be described after which the novel features will be pointed out in the appended 60 claims.

Fig. 1 is a side view partially broken away of a portion of a sewing machine embodying my invention;

Fig. 2 is an under side view of the bed frame;

Fig. 3 is a plan view of the portion of the bed frame on which the work is supported and showing the improved thread-cutting 70 mechanism;

Fig. 4 is a view of the turret showing the means for drawing off the under thread and the cord;

Fig. 5 is an edge view of the turret shown 75 in Fig. 4;

Fig. 6 is a top plan view;

Fig. 7 is a view showing the manner in which the pull-off device operates;

Fig. 8 is a vertical sectional view showing the position of the work and the threads at the time the thread-cutting mechanism operates;

Fig. 9 is a plan view of the thread-cutting device showing it in thread-cutting position.

Fig. 10 is a fragmentary view of the cutting edges of the thread-cutting device.

While my invention is applicable to buttonhole sewing machines of various types I 90 have chosen herein to illustrate it as it would be applied to a buttonhole sewing machine of the well-known "Reece" type, exemplification of which may be found in United States Patent No. 655,637, August 7th, 1900 95 and No. 862,238, August 6th, 1907. Such sewing machines are provided with work-holding means for holding the work and stitch-forming mechanism for forming the stitches along the edge of the buttonhole.

The work-holding means is herein shown as mounted on the bed plate 1 of the machine and as comprising work clamps 2 that are adapted to clamp the work *w* against clamp plates 3. The stitch-forming mechanism comprises the usual upper needle 4 operating from above the work and suitable under thread-handling mechanism operating

beneath the work and mounted on a turret 5, the latter having the throat plate 28 provided with an opening. In the sewing machine herein illustrated the needle 4 and the 5 turret 5 supporting the under thread-handling mechanism are carried by a frame or head 6 which has the overhanging arm 7 in which reciprocates the needle bar 8 carrying the needle 4 and which also has the turret- 10 supporting portion 9 situated beneath the work and in which the turret 5 is rotatably mounted.

The under thread-manipulating mechanism may have any desirable construction 15 such for instance as that shown in either of said patents. That herein shown is of the two looper variety illustrated in the above-mentioned Patent No. 862,238, August 6th, 1907, and it comprises two loopers 10 and 11 carried by an oscillating block 12 which is connected by a link 13 to a spindle 14 situated axially of the turret and reciprocable vertically. The reciprocations of the spindle 14 oscillate the loopers in timed relation with the reciprocation of the needle 4 to produce the stitches, all as described in said above-mentioned patent.

In the construction herein shown the looper 10 is a thread-carrying looper, it 30 having an eye through which the under thread 24 is threaded, said thread passing through the sleeve 14 and around a suitable tension device 16 carried by the turret, all as usual in sewing machines of this type. Both 35 the turret and the needle bar are mounted for rotary movement about a vertical axis to provide for stitching around the ends of the buttonhole, such movement being secured from the rock shaft 17 which has two segment gears 18 (only one of which is herein shown) that mesh with gears 19 and 20 on the needle bar holder and turret respectively.

In these sewing machines the stitch-forming mechanism and the work-holding means 45 have a relative movement, both during the stitching on the buttonhole and before and after the stitching and such relative movement may be provided for either by moving the work-holding means relative to the 50 stitch-forming mechanism or moving the stitch-forming mechanism relative to the work-holding means. In the construction herein shown the work-holding means are 55 stationarily mounted on the bed plate 1 and the frame 6 which carries the stitch-forming mechanism is mounted to move back and forth on the bed plate, but the invention which is hereinafter described is equally 60 applicable to sewing machines in which the relative movement is produced by a movement of the work-holding means rather than of the frame 6.

21 indicates the usual buttonhole cutter by which the buttonhole slit is cut. The relative movement between the stitch-forming

mechanism and work-holding means is produced by means of the main cam 22 which is situated beneath the bed frame and this cam also actuates the buttonhole cutter 21 in proper timed relation.

The parts thus far described are or may be all as usual in buttonhole sewing machines of this type and form no part of the present invention and inasmuch as their operation is well known to those skilled in the art it will not be necessary to rehearse it here.

It may be briefly stated, however, that when the machine comes to rest at the end of a buttonhole the work-holding means and 70 stitch-forming mechanism are in the relative position shown in full lines Fig. 1 with the needle 4 considerably in advance of the sewing point and with the work in button-hole-cutting position. When the machine is 75 started in operation the frame 6 with the stitch-forming mechanism moves backwardly to bring the needle into the dotted line position or into buttonhole-stitching position and at this time the shaft 23 for driving the 80 stitch-forming mechanism is set in operation and the stitching on the buttonhole begins. During the stitching the frame 6 continues 85 to move backwardly to cause the stitching to be formed down one side of the buttonhole and then moves forwardly to the dotted line 90 position Fig. 1, thereby forming the stitches on the opposite side of the buttonhole. When the stitching is completed the stitch-forming mechanism comes to rest and then 95 the frame moves forwardly again to the position shown in Fig. 1, thus bringing the work into buttonhole-cutting position. The buttonhole cutter is actuated while the work 100 is in buttonhole-cutting position and either 105 after the stitching on the buttonhole is completed or before the stitching is started.

As stated above one feature of the present invention relates to means for cutting the under thread 24 and the cord 25 at the end 110 of the stitching operation. When the stitching on the buttonhole has been completed and the stitch-forming mechanism comes to rest the needle 4 will be in the dotted line position Fig. 1, the throat plate 28 will be 115 directly beneath the needle and in the dotted line position Fig. 3, and the under thread 24 and cord 25 will extend from the work 120 w directly downwardly through the throat plate. When the frame 6 and stitch-forming mechanism move forwardly into the full line position or into buttonhole-cutting position the throat plate will be carried into 125 position shown in full lines in Fig. 3 and in Fig. 8 and a length of the under thread 24 and cord 25 will extend substantially horizontally from the work to the throat plate as seen in Fig. 8.

My improved thread-cutting means is constructed to cut this horizontally-extending 130

portion of the under thread and cord close to the work. The thread-cutting device comprises two co-operating cutting elements 26, 27 which are pivotally mounted so 5 that they have a scissors-like action. These cutting elements are shown as secured to two blocks 29 and 30 which are pivotally mounted at 31 on the plate 32 carried by the bed frame.

10 The block 29 is provided with an arm 33 and the block 30 is provided with a similar arm 34, the two arms extending parallel to each other and being separated from each other. Situated between the two arms is 15 a cam device 35, which is turnable about a vertical axis and which when turned clockwise in Fig. 3 acts against the arms 33 and 34 thereby spreading the same and closing the shearing members 26, 27 together. The 20 two arms 33, 34 are connected by a spring 36, which tends to hold the shears open in the position shown in Fig. 3.

The cutting or shearing edges of the cutting members 26, 27 extend substantially 25 vertically and as the cam 35 operates to actuate the cutting members these cutting edges act on and sever the cord and under thread close to the work. The construction is such that the cutting of the thread and 30 cord is done by the upper portion of the cutting edges and in order to obviate any possibility that the cord or thread will be crowded upwardly out of the shearing edges when they are brought into cutting position 35 I will preferably make the shearing edges of substantially the shape shown in Fig. 10. The cutting member 26 is formed with a notch 81 in its upper edge which provides a horn or point 82 and the shearing edge 83 of the member 27 is preferably 40 formed on an inclination. When these shearing edges come together and move past each other the points 82 and 84 of the shearing edges will pass over the thread 24 and 45 cord 25 and prevent them from being forced upwardly out from between the shearing edges. The notch 81 forms a recess in which the thread and cord are received and retained 50 during the thread-cutting operations thus preventing said cord and thread from being moved either upwardly or downwardly while they are being cut. Furthermore since both 55 of the cutting elements are pointed when they move toward each other the points will tend to crowd in between the work and the horizontally-extending thread and stay cord and thus separate the thread and stay cord from the work, said thread and stay cord being forced downwardly rather than upwardly and carried into the notch 81.

The cord 25 which is used in buttonhole sewing machines is usually considerably larger and heavier than the under thread and in order to successfully sever it the

thread-cutting mechanism must operate with 65 considerable force.

The construction herein provided is positive in its action and will readily sever the heaviest cord which is used in buttonhole 70 sewing machines.

The cam 35 may be actuated by any suitable means at the proper point in the cycle of operations. In the construction herein shown this cam is actuated from the main cam 22. For this purpose the cam 35 is 75 mounted on a stud 37 which is journaled in the plate 32 and which projects below said plate, the projecting portion having an arm 38 fast thereon which is engaged by the shoe portion 39 of a lever 40 which is fast on a 80 rock shaft 42 that is mounted in the housing 41 of the cam 22. This rock shaft has an arm 43 rigid therewith which is adapted to be engaged by a roll 44 that is rigid with the main cam 22. For this purpose the main 85 cam is provided with a hub extension 45 carrying an arm 46 on which the roll 44 is mounted.

The roll is so positioned that the latter will engage the arm 43 after the stitch-forming mechanism has come to rest and just as the frame 6 completes its movement by which the needle is carried from the dotted to the full line position Fig. 1. The swinging of the arm 43 and lever 40 by the roll 90 44 operate through the arm 38 to swing the cam 35 into the position shown in Fig. 9, thereby closing the cutting elements 26, 27 and severing the under thread 24 and the cord 25. As soon as the roll 44 wipes by the end of the arm 43 the lever 40 will be returned to its normal position by a spring 95 73 and the cutting elements will be opened again by the spring 36, this occurring just as the machine is brought to rest.

When the parts move into buttonhole-cutting position the tension on the under thread 24 and cord 25 will tend to draw the work downwardly and in order to avoid any 100 possibility of the shears cutting the work as well as the thread and cord I have provided a guard plate 47 which is attached to the plate 32 and which extends over the shears. The work rests on this plate 47 and is prevented thereby from being drawn 110 down into the path of movement of the shearing edges.

The invention also comprises means acting on the under thread 24 to draw off a length of the latter from the source of supply just 115 before the cutting operation takes place, the purpose of this being to provide a sufficient length of thread to ensure the proper formation of the first stitch when the stitching operation is begun again.

The pulling off of the under thread is accomplished by a pull-off finger 48 which operates directly beneath the throat plate 28

and which is carried by a vertically-extending rock shaft 49 that is journalled in a bracket 72 carried by the turret 5. Normally the pull-off finger 48 stands in the position shown in Fig. 6 but at the proper point in the cycle of operations the rock shaft 49 is turned so as to cause the pull-off finger to swing across the throat plate into the position shown in Fig. 7 thereby engaging the under thread 24 and drawing off a length thereof from the source of supply. This swinging movement of the pull-off arm is herein secured by or through the rotation of the turret and the relative movement between the stitch-forming mechanism and work-holding means by which the parts are carried from stitching to buttonhole-cutting position. For this purpose the rock shaft 49 is provided at its lower end with a crank 20 arm 71 having a crank pin 50 which is connected by a link 51 to a swinging lever 52 pivoted to the turret at 53 and acted on by a spring 54 which normally holds it in the position shown in Fig. 4, in which position the pull-off arm will be in the position shown in Fig. 6. When the parts are in this position the outer edge of the lever 52 stands outside of the edge 55 of the turret. A swinging movement of the lever 52 inwardly will operate to give the pull-off arm 48 its thread-pulling movement. Such swinging movement of the lever 52 is derived from a cam 56, which is carried on an arm 57 secured to the bed frame.

In sewing machines of this type the turret is given a rotation to carry the stitching around the end of the buttonhole as the buttonhole is completed and when the stitch-forming mechanism has been brought to rest the frame 6 is moved forwardly to bring the parts into the buttonhole-cutting position represented by the full lines Fig. 1. At this point the turret is given a backward rotation to bring it to its initial position. When the stitching on the buttonhole is completed the turret has been turned into a position 180° from that shown in Fig. 2, in which position the lever 52 is on the same side of the turret as the cam 56. This is the position the turret occupies when the frame 6 is moved forwardly to carry the parts into buttonhole-cutting position and during such forward movement the lever 52 engages and wipes by the cam 56 as shown in Fig. 7, thereby swinging the lever inwardly and through the link 51 and crank pin 50 giving the pull-off lever 48 its thread-pulling movement into the position shown in Fig. 7. As the lever 52 wipes by the high point of the cam 56 the pull-off lever will be allowed to back up slightly thus giving up some of the thread. This slack, however, is taken up by the forward movement of the turret and when the forward movement of the frame 6 is completed and the parts are in the positions

shown in Figs. 1 and 8 the thread between the throat plate and the work will be taut. The pull-off finger 48 still engages the thread at this time. After the frame 6 has been brought to the limit of its forward movement and into buttonhole-cutting position the buttonhole cutter is actuated to cut the buttonhole (that is, provided the machine is of the type in which the buttonhole is cut after the stitching is completed,) and while the buttonhole is being cut the turret is given a backward rotation to bring it into the position shown in Fig. 2. During such backward rotation of the turret the lever 52 is carried out of engagement of the cam 56 and the pull-off arm 48 resumes its normal position shown in Fig. 6 thereby giving up the thread which had been pulled off.

The lever 52 also functions to relieve the tension on the under thread and for this purpose the upper end 58 of the lever is adapted to enter between the disks of the tension 16 and spread the latter, this occurring at the same time that the arm 48 has its thread-pulling movement.

I claim:

1. In a two-thread buttonhole sewing machine, the combination with work-holding means, of stitch-forming mechanism constructed to concatenate the upper and under threads to form the edge stitches along the buttonhole, a throat plate located closely below the work and through which the under thread is led to the work, means to give the stitch-forming mechanism and work-holding means relative horizontal feeding movements, and a further relative movement after the buttonhole is sewed, whereby a length of the under thread is drawn through the throat plate and extends between the throat plate and the work in a substantially horizontal direction, a pair of relatively movable cutting elements pivotally mounted to turn about a common vertical axis which is stationary relative to the work-holding means, one of which cutting elements is tapered toward its extremity, means actuating said cutting elements first to thrust the nose of said tapered element between the work and the horizontally-extending thread after the buttonhole is completed and after said further relative movement thereby to crowd or wedge apart the thread and the work and thereafter to cut the thread close to the work.

2. In a two-thread buttonhole sewing machine, the combination with work-holding means, of stitch-forming mechanism constructed to lay a cord along the edge of the buttonhole and to concatenate the upper and under threads to form the edge stitches along the buttonhole, a throat plate located closely below the work and through which the under thread is led to the work, means to give the stitch-forming mechanism and

work-holding means relative horizontal feeding movements during the sewing and a further relative movement after the button-hole is sewed, whereby a length of the under 5 thread and cord is drawn out through the throat plate and extends between the throat plate and the work in a substantially horizontal direction, a pair of relatively movable cutting elements situated beneath the 10 work and pivotally mounted to turn about a common vertical axis which is stationary relative to the work-holding means, one of which cutting elements is tapered toward its extremity, means actuating said cutting elements first to thrust the nose of said tapered 15 element between the work and the horizontally-extending thread and cord after the buttonhole is completed, thereby to separate the thread and cord from the work and then 20 to cut said thread and cord close to the work.

3. In a sewing machine, the combination with work-holding means, of stitch-forming mechanism, a main cam for producing a relative movement between the stitch-forming mechanism and work-holding means, means to cut the thread beneath the work comprising a pair of pivotally-mounted cutting elements each having an arm, a cam member 25 situated between said arms, a rock shaft carrying said cam member, and means associated with the main cam to actuate the rock shaft.

4. In a buttonhole sewing machine, the combination with work-holding means, of stitch-forming mechanism constructed to lay a cord along the edges of the buttonhole and form buttonhole stitches over the cord a main cam for producing a relative movement 35 between the stitch forming mechanism and work-holding means, of means to cut both the cord and the thread beneath the work, said means comprising a pair of pivotally-mounted cutting elements each having an 40 arm, a cam member situated between said arms, a rock shaft carrying said cam member and means associated with the main cam to actuate the rock shaft.

5. In a sewing machine, the combination with work-holding means, of stitch-forming mechanism adapted to perform a predetermined sewing operation and then come to rest, said stitch-forming mechanism including means for manipulating both the upper 50 and under threads, a turret on which the under thread-manipulating mechanism is mounted, a throat plate carried by the turret and through which the under thread is led to the work, means to give the stitch-forming mechanism and work-holding means a relative movement after the stitch-forming mechanism has come to rest, whereby a length of under thread is drawn through the 55 throat plate and extends from the work to the throat plate in a substantially horizontal direction, a pair of cutting elements co-axially pivoted to turn about a common vertical axis having a stationary position relative to the work-holding means, and cam means acting on the cutting elements to cause them to turn about their common axis 60 to cut the thread close to the work.

6. In a sewing machine, the combination with work-holding means, of stitch-forming mechanism adapted to perform a predetermined sewing operation and then come to rest, said stitch-forming mechanism including means for manipulating both the upper and under threads, a turret on which the under thread-manipulating mechanism is 65 mounted, a throat plate carried by the turret and through which the under thread is led to the work, means to give the stitch-forming mechanism and work-holding means a relative movement after the stitch-forming mechanism has come to rest, whereby a length of under thread is drawn through the throat plate and extends from the work to the throat plate in a substantially-horizontal direction, and cutting elements having substantially vertical cutting edges to cut the 70 thread close to the work.

7. In a sewing machine, the combination with work-holding means, of stitch-forming mechanism adapted to perform a predetermined sewing operation and then come to rest, said stitch-forming mechanism including means for manipulating both the upper and under threads, a turret on which the under thread-manipulating mechanism is 75 mounted, a throat plate carried by the turret and through which the under thread is led to the work, means to give the stitch-forming mechanism and work-holding means a relative movement after the stitch-forming mechanism has come to rest, whereby a length of under thread is drawn through the throat plate and extends from the work to the throat plate in a substantially-horizontal direction, two cutting elements pivoted to 80 turn about a common vertical axis which is stationarily mounted relative to the work-holding means, each cutting element having a substantially vertical cutting edge, and means to actuate said elements to cut the 85 thread close to the work.

8. In a buttonhole sewing machine, the combination with work-holding means, of stitch-forming mechanism constructed to lay a cord along the edge of the buttonhole and to concatenate the upper and under threads 90 to form the edge stitches along the button-hole, a turret on which the under thread-manipulating mechanism is mounted, a throat plate carried by the turret and through which the under thread and cord are led to the work, means to give the stitch-forming mechanism and work-holding means a relative movement after the button-hole is sewed, whereby a length of under 95

thread and cord is drawn through the throat plate and extends from the latter to the work in a substantially-horizontal direction, a pair of cutting elements situated beneath the work and pivoted to turn about a common vertical axis which is stationarily mounted relative to the work-holding means, and means to actuate said cutting elements to cut the under thread and cord close to the work.

9. In a buttonhole sewing machine, the combination with work-holding means, of stitch-forming mechanism constructed to lay a cord along the edge of the buttonhole and to concatenate the upper and under threads to form the edge stitches along the buttonhole, a turret on which the under thread-manipulating mechanism is mounted, a throat plate carried by the turret and through which the under thread and cord are led to the work, means to give the stitch-forming mechanism and work-holding means a relative movement after the buttonhole is sewed, whereby a length of under thread and cord is drawn through the throat plate and extends from the latter to the work in a substantially-horizontal direction, and

thread-cutting means having vertical shearing edges to cut the cord and thread close to the work.

10. In a sewing machine, the combination with work-holding means, of stitch-forming mechanism, a throat plate through which the thread is led to the work, means to give the stitch-forming mechanism and work-holding means a relative feeding movement during the sewing operation and a further relative movement after the sewing is completed, whereby a length of thread is drawn through the throat plate and extends between the throat plate and the work, a guard plate stationarily mounted relative to the work-holding means and situated in a plane between the work and the throat plate, a pair of relatively movable cutting elements operating beneath the guard plate, and means to actuate said elements after said further relative movement has been completed thereby to cut close to the work the length of thread extending from the work to the throat plate.

In testimony whereof, I have signed my name to this specification.

JOHN KIEWICZ.
